QUICK ADJUSTABLE WRENCH

Fred A. Ollmann, Gresham, Wis.

Application August 1, 1944, Serial No. 547,540

4 Claims. (Cl. 81—106)

The present invention relates to new and useful improvements in wrenches of a type designed for use as a pipe wrench and for other purposes, and the invention has for its primary object to provide a movable jaw and a stationary jaw together with means for the quick adjustment of the movable jaw relative to the fixed jaw.

A further object is to provide a wrench of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the jaws of the wrench in a substantially closed position and with the shanks of the jaws locked against quick adjusting movement.

Figure 2 is a similar view showing the shanks of the jaws in position for quick adjustment thereof.

Figure 3 is a side elevational view showing the jaws in open position.

Figure 4 is a perspective view of the sleeve forming the guide for the shanks of the jaws.

Figure 5 is an enlarged perspective view of the cam locking member for the shanks of the jaws.

Referring now to the drawings in detail wherein for the purpose of illustration I have disclosed a preferred embodiment of the invention, the numeral 5 designates the handle of the wrench having the shank 6 of a stationary jaw 7 extending from the handle.

A U-shaped guide 8 has its ends pivoted to the shank 6 adjacent its outer ends by means of a pin 9.

The movable jaw 10 includes a shank 11 positioned substantially parallel to the shank 6 and slidably mounted in the guide 8.

A sleeve 12 slidably receives the shank 11, the shank 11 being adjusted relative to the sleeve by means of the knurled nut 13 threadedly engaged with the threads 14 on the edges of the shank, the nut working in the openings 15 in the opposite sides of the sleeve.

The lower edge of the sleeve 12 is formed with a guide 16 slidably receiving the shank 6 of the stationary jaw and the front edge of the sleeve is formed with a pair of spaced parallel down-

wardly extending legs 17 disposed at opposite sides of the shank 6.

The upper edge of the shank 6 is formed with notches 18 adapted for receiving a pin 19 extending transversely of the sleeve 12 at the upper portion of the legs 17.

A pin 20 is carried at the lower portion of the legs 17 and extends transversely beneath the shank 6 and on which is rotatably mounted a cam 21 positioned between the legs 17, the cam including an eccentrically formed cam hump 22 and a finger-grip 23 extending from the pivotal mounting of the cam in a direction angularly with respect to the hump 22.

As shown in Figure 1 of the drawings when the finger-grip 23 is moved forwardly the cam hump 22 will engage the lower edge of the shank 6 whereby to move the shank upwardly toward the shank 11 with the pin 19 seated in one of the notches 18. With the parts in this position adjustment of the jaws 7 and 10 is accomplished through the nut 13 and the threads of the shank 11.

However, when a quick adjustment of the jaws 7 and 10 is desired, the finger-grip 23 is moved downwardly whereby to release the cam hump 22 from the lower edge of the shank 6 and the shank 6 may be moved relative to the shank 11 in a downward direction to disengage the pin 19 from the notches 18 as shown in Figure 2 of the drawings and a quick adjustment of the jaws may then be made. The finger-grip portion 23 of the cam is then returned to the position as shown in Figure 1 which locks the jaws in their quick adjusted position.

It is believed that the details of construction and manner of use of the device will be readily understood from the foregoing without further detailed explanation.

Having described the invention, what is claimed as new is:

1. A wrench including a stationary jaw and a movable jaw, said jaws having shanks disposed substantially in parallelism, a sleeve slidably receiving said shanks, threaded adjusting means between the shank of the movable jaw and the sleeve, a pin carried by the sleeve extending transversely of the shank of the stationary jaw, notches in one edge of the shank of the stationary jaw adapted for receiving said pin and actuating means between the sleeve and the opposite edge of the shank of the stationary jaw for locking and releasing the pin from said notches to provide for the quick adjustment of said last-named shank.

2. A wrench including a stationary jaw and a movable jaw, said jaws having shanks disposed substantially in parallelism, a sleeve slidably receiving said shanks, threaded adjusting means between the shank of the movable jaw and the sleeve, a pin carried by the sleeve extending transversely of the shank of the stationary jaw, notches in one edge of the shank of the stationary jaw adapted for receiving said pin, a cam device pivotally attached to the sleeve and engageable with the opposite edge of the shank of the stationary jaw and finger-gripping means carried by the cam for operating the latter in a manner to engage and disengage the pin from the shank of said stationary jaw.

3. A wrench comprising a movable jaw and a stationary jaw, each of said jaws including a shank disposed in substantial parallelism, a sleeve slidably receiving the shanks, a threaded adjusting means between the sleeve and the shank of the movable jaw, a pair of spaced parallel legs extending downwardly from the sleeve, a pin extending transversely of the legs between the shanks, notches on the upper edge of the shank of the stationary jaw adapted for selectively receiving the pin, and a manually operable

cam pivoted on the legs and engageable with the lower edge of the shank of said stationary jaw to move the latter into and out of engagement with said pin to provide for the quick adjustment of the jaws relative to each other.

4. A wrench comprising a movable jaw and a stationary jaw, each of said jaws including a shank disposed in substantial parallelism, a U-shaped guide carried at the front end of the stationary shank and slidably receiving the movable shank, a sleeve slidably receiving the shanks, a threaded adjusting means between the sleeve and the shank of the movable jaw, a pair of spaced parallel legs extending downwardly from the sleeve, a pin extending transversely of the legs between the shanks, notches on the upper edge of the shank of the stationary jaw adapted for selectively receiving the pin, and a manually operable cam pivoted on the legs and engageable with the lower edge of the shank of said stationary jaw to move the latter into and out of engagement with said pin to provide for the quick adjustment of the jaws relative to each other.
